UNITED STATES PATENT OFFICE

2,526,380

TOOL FOR LEVELING PROTUBERANCES
IN SHEET METAL

Albert L. Mathews, Greensboro, N. C.

Application February 24, 1948, Serial No. 10,513

1 Claim. (Cl. 153—32)

1

This invention relates to a pneumatic hammer which is particularly adapted for use in beating out very small depressions in the surfaces of sheet metal such as in automobile body work.

Heretofore, it has been accepted practice to hold the pointed end of a sharp instrument, such as an ice pick, against a small convex surface of sheet metal which, of course, was concave on the opposite side. The other end of the ice pick was then tapped lightly and repeatedly by a hammer; not with enough force to cause the pointed end of the ice pick to penetrate the sheet metal, but to cause minute outward projections, not unlike coarse sandpaper, on the said opposite surface of this sheet metal. The rough surface is then filed off and prepared in the usual manner for painting. This procedure is extremely difficult in confined areas and in many instances requires the removal of upholstery and other obstructions when repairing surfaces such as automobile door panels.

It is therefore an object of this invention to provide a tool having a reciprocating plunger therein, the movement of said plunger being controlled by means remotely disposed from the plunger and said plunger being disposed within a housing which may be held in one hand thus permitting access to very confined areas.

Some of the objects of the invention having been stated, other objects will appear as the description proceeds, when taken in connection with the accompanying drawings, in which:

Figure 1 is an elevation showing the tool with the plunger in engagement with a small portion of sheet metal and showing a valve and a compressed air tank which are associated therewith;

Figure 2 is a vertical sectional view taken along the line 2—2 in Figure 1 omitting the sheet metal;

Figure 3 is a vertical sectional view taken along the line 3—3 in Figure 1;

Figure 4 is an elevation being partly in section and taken substantially along the line 4—4 in Figure 1;

Figure 5 is a vertical sectional view of the central portion of Figure 3 with the valve in a different position;

Figure 6 is a plan view, with parts in section, and taken along the line 6—6 in Figure 3.

Referring more specifically to the drawings, the numeral 10 indicates a source of compressed air, such as a motor compressor or a compressed air tank, having connected thereto as at 11, by a suitable fitting 9, a flexible hose 12 which extends upwardly in Figure 1 and the other end of the hose 12 has a fitting 8 which is threadably mounted in a threaded bore 1 in a conventional Schrader blow gun valve 15, such as that shown in United States Letters Patent No. 1,957,567 and is described here as a means to clearly define the

action of this invention. However, there are many types of valves which could be used in association with this invention and it is not desired to confine the invention to this particular valve.

By referring to Figure 3, it may be observed that the valve 15 has a port hole 16 for the ingress of air from the source of compressed air and the air will pass through this port hole 16 into a chamber 17 in which is mounted, for vertical sliding movement therein, a disk 18, the lower end of which is engaged by the upper end of a compression spring 19, the lower end of which engages the bottom of the chamber 17.

Integral with and extending from the uppermost surface of the disk 18 is a stem 22 which tapers inwardly toward its upper end and this portion 22 extends upwardly through an opening 23 in a valve seat 24. The topmost surface of the stem 22 is engaged by a disklike portion 25 which has integral therewith and extending upwardly therefrom, a shaft 26 which has integral therewith a thumb-press head 27 and disposed immediately below the thumb-press head 27 is a resilient rubber washer 30.

The shaft 26 extends upwardly through and slidably penetrates a ferrule 31 having a plurality of vertically disposed bores 32 therethrough which are disposed around the shaft 26. It may be observed in Figure 3 that the compression spring 19 has urged the thumb-press head 27 upwardly and the disk portion 25 is resting against the top end of a bore 33 in the lower surface of the ferrule 31. It is obvious that with the head 27 in this uppermost position, the disk 18 will have passed above the port hole 16 and thus the air coming from the source of compressed air 10 through the flexible hose 12 will not be able to pass through the valve 15. However, when the thumb-press head 27 is moved downwardly from the position shown in Figure 3 to the position shown in Figure 5, the disk 18 will permit air to pass through the port hole 16 and upwardly and into the chamber 17 and through the opening 23 and thus the air will pass through an opening 35 which is adjacent the lower end of the ferrule 31. The air will pass through the opening 35 into a bore 36 which is threaded at its open end as at 44 in which an elbow 37 is threadably mounted. Connected to the other end of elbow 37 is one end of a union 38. The other end of the union 38 is threadably connected to a fitting 34 on one end of a flexible hose 40 which extends upwardly and has a fitting 41 connected to a downturned portion 42 (Figure 1) of a cylinder base 43. The cylinder base 43 and the downwardly projecting portion 42 are parts of the tool broadly designated at 45. The downturned portion 42 and the cylinder base 43 have interconnecting bores 49 and

39 (Figure 2) therein for passage of air between the flexible hose 40 and a cylinder to be presently described.

The cylinder base 43 threadably engages one end of a cylinder 46 and secured to the other end of the cylinder 46, by any suitable means such as welding 48, is a cylinder head 47. The cylinder head 47 is penetrated by a plurality of bores 50 and the outer surface of the cylinder head 47 has an annular groove 51 therein which also has an annular countergroove 52 adjacent thereto and disposed in the outer surface of the cylinder head 47. The countergroove 52 forms a shoulder 53 against which a screen wire member 55 is disposed and the outer edges of the cylinder head 47 are crimped inwardly as at 56 to confine the screen wire 55 against the shoulder 53. The screen wire covers the annular groove 51.

Extending outwardly from the cylinder head 47 and disposed in the center thereof is a portion 57 having a bore 60 therethrough which slidably receives a plunger 61. The plunger 61 has a collar 62 mounted thereon and the collar 62 engages the outward end of the portion 57 of the head end 47 thus limiting inward movement of the plunger 61. The plunger 61 has a bore 64 therein in which a pin 65, having a pointed end 66, is mounted. The pin 65 is confined in the bore 64 by a set screw 67 which loosely penetrates the collar 62 and threadably penetrates the plunger 61 and not only secures the pin 65 in the bore 64, but also secures the collar 62 on the end of the plunger 61.

The plunger 61 which extends inwardly into the cylinder 46 and has a head portion 68 integral therewith which is engaged by a compression spring 70 which is disposed around the plunger 61, extends to and engages the inner surface of the head end 47. Disposed around the compression spring 70, as well as the plunger 61 and the headed portion 68 of the plunger 61, is a larger compression spring 72 which also engages the inner surface of the cylinder head 47 and extends to the right, as observed in Figure 2, and rests in an annular groove 74 in a piston 75. The groove 74 defines a projecting portion 76 in the center of the piston 75 which is encircled by one end of the spring 72.

When air is admitted through the chamber 36 of the valve 15 as heretofore described, it will continue through the elbow 37 and the pipe 40 to the cylinder base 43 of the tool 45 and thus the piston 75 will be urged to the left as observed in Figure 2. The portion 76 then engages the head portion 68 of the plunger 61 and thus moves the plunger 61 outwardly relative to the cylinder 46. Upon releasing the thumb-press head 27 the compression spring 19 will urge the parts from the position shown in Figure 5 to the position shown in Figure 3 and thus the air which has formerly entered the cylinder 46 will return through the pipe 40 and into the bore 36 and through the port hole 35. The air will then escape upwardly through the bores 32 in the ferrule 31. This will permit the piston 75 to be urged to the right, as observed in Figure 2, by the compression spring 72 and will also permit the plunger 61 to be urged to the right as observed in Figure 2, by the compression spring 72 and will also permit the plunger 61 to be urged to the right as observed in Figure 2 by the compression spring 70.

Thus by holding the tool 45 in the one hand, the pointed end 66 of the pin 65 may be held against an inwardly projecting portion 80 of a

sheet metal member 81 and by rapidly reciprocating the thumb-press head 27 with one's thumb as the valve 15 is held in the other hand, the point 66 of the pin 65 will gradually move the projecting portion 80 of the sheet metal member 81 outwardly by the reciprocatory action thus imparted thereto and the sheet metal will be left relatively smooth at which time a file may then be used against the exterior surface of the same for the final working of the metal as is conventional practice.

In the drawings and specification, there has been set forth a preferred embodiment of the invention, and although specific terms are employed, they are used in a generic and descriptive sense only and not for purposes of limitation, the scope of the invention being defined in the claim.

I claim:

In a pneumatic means for leveling protuberances in sheet metal, a source of compressed air, a cylinder, a hose leading from the source of compressed air to one end of the cylinder, a manually movable valve disposed in the hose, a spring means for holding the valve in one position and the valve being manually movable to another position to allow air under pressure to flow into the cylinder and being movable to another position to cut off the flow of air under pressure into the cylinder and to allow escape-
ment of the air therefrom, said cylinder comprising a reciprocable piston, said piston having an annular groove therein, said groove defining a projecting portion on the center of the piston, a compression spring having one end mounted in the annular groove, the other end of the compression spring being mounted against the other end of the cylinder, a plunger mounted in the cylinder and extending from one end thereof, a pointed member carried by the plunger for engaging a protuberance, admission of compressed air into the cylinder serving to move the projecting portion of the piston into contact with the plunger to move the same outwardly with respect to the cylinder to cause the pointed member to engage the protuberance, the end of the plunger next to the piston being enlarged, a second compression spring surrounding the plunger and having one end resting against the enlarged head of the plunger and having its other end resting against the other end of the cylinder and tending to move the plunger to retracted position with respect to the cylinder, the compression spring disposed between the piston and the other end of the cylinder serving to return the piston to the said one end of the cylinder through which compressed air is admitted when the compressed air is cut off from the cylinder and vented from the cylinder by means of said valve.

ALBERT L. MATHEWS.
